UNITED STATES PATENT OFFICE.

WALTER B. TEMPLETON, OF CHICAGO, ILLINOIS.

LIFTING APPLIANCE

1,321,950.

Specification of Letters Patent. Patented Nov. 18, 1919.

Application filed January 17, 1912. Serial No. 212,164.

To all whom it may concern:

Be it known that I, WALTER B. TEMPLETON, a citizen of the United States, residing at Chicago, in the county of Cook and State 5 of Illinois, have invented certain new and useful Improvements in Lifting Appliances, of which the following is a specification.

This invention relates to new and useful improvements in lifting appliances, and has 10 reference more particularly to a device in the general nature of a portable crane, and embodying structural features of the tool commonly known as a lifting jack.

The principal object sought to be attained 15 by the invention is the production of an improved lifting tool of that type wherein the upright frame member carrying the lifter rack and its actuating devices can be adjusted to and rigidly held in any desired 20 angle between a vertical position and a considerably inclined position. Other objects 25 of the invention are to provide a tool readily adapted, especially in the inclined position, for use in connection with a lifting hook and chain, or like appliances, suspended 30 from its upper end; to provide a construction whereby such lifting chain and hook, or like appliance, may readily be adjusted to positions in front of or on either 35 side of the main frame of the jack; to provide a construction whereby the operating arm or lever can be applied at the most advantageous angle, whether the frame be in a vertical or in an inclined position; and to 40 provide a construction whereby the angular adjustment of the frame to the base can be effected with a minimum of time and labor, and without the necessity of employing clamping devices for securing the frame and 45 base in their various relatively adjusted positions. Still other objects and advantages of the invention will be apparent from the subjoined description, taken in connection with the accompanying drawings forming a part of this specification, in which,—

Figure 1 is a side elevation of the preferred embodiment of the invention, the jack frame and the rack bar being shown as vertical;

50 Fig. 2 is a view similar to Fig. 1, but showing the jack frame and rack bar adjusted to an inclined position, and a chain and grapple hook suspended from the upper end or head of the rack bar;

55 Fig. 3 is a top plan view of the swiveled head of the rack bar shown in Figs. 1 and 2;

Fig. 4 is a central vertical section through the swiveled head and the rack bar tenon on which it is mounted;

Fig. 5 is a detail in vertical section through the base member and the lower portion of one side of the frame, showing in full lines the coöperating teeth on the base and frame;

Fig. 6 is a front elevation of the base and lower end of the frame;

Fig. 7 is a side elevation, partly broken out, of the base and lower end of the frame, and illustrating a modified construction as compared with Figs. 1 to 6 inclusive;

Fig. 8 is a front elevation of the base and lower end of the frame as shown in Fig. 7;

Fig. 9 is a side elevation, corresponding to Fig. 7, of a further modification;

Fig. 10 is a front elevation of the structure shown in Fig. 9;

Fig. 11 is a vertical section on the line 11-11 of Fig. 10;

Fig. 12 is a top plan view, similar to Fig. 3, of a modified form of swivel head for the rack bar;

Fig. 13 is an elevation, broken out between its ends, of the improved handle bar or lever.

Referring first to Figs. 1 to 6 inclusive, 1 designates as an entirety the main frame or casting of a lifting jack, 2 the ordinary rack bar slidably mounted therein and terminating at its lower end in a laterally projecting lifter foot 3. 4 designates a head member swiveled on the upper end of the 20 rack bar 2, 5 designates as an entirety the socket member for the operating handle or lever, and 6 designates the base. In carrying out the invention, the base member 6 is provided with a pair of parallel upstanding lugs 7, on the rounded upper edges of 25 which are formed a series of ratchet teeth 8. Each of the lugs 7 is also centrally apertured to receive a short pivot pin 9. The lower ends of the side walls of the jack 30 frame 1 are also formed with ratchet teeth 10 that rest upon and coöperate with the ratchet teeth 8; and said walls are further provided with laterally offset depending lugs or extensions 11 that overlap the outer 35 sides of the base lugs 7, and are provided with slots 12 engaging the outer ends of the pivot pins 9. On the rear of the base member 6 is formed a stop shoulder 13 that co- 40 operates with the lower end of the back wall of the frame to limit the back swing 45 of the latter to the vertical position.

The socket member 5, which is fulcrumed in the main frame or casing 1, is provided with a pair of sockets 5^a and 5^b disposed at an angle to each other, and both adapted 5 to receive the removable handle member 14.

On the upper end of the rack bar 2 is formed a tenon 15 (Fig. 4) that engages an undercut socket 16 in the lower side of the head member 4. The head member 4 is 10 formed with a pair of oblique oppositely disposed notches 17 adapted to seat a pair of links 18 of a chain, the intermediate link 19 connecting the links 18 lying flat upon the upper end of the head 4, all in the manner clearly indicated in Fig. 2. At the lower end of the chain formed by the links 18 and 19 is a grapple hook 20. The swiveled head 4 may easily be secured on the upper end 15 of the rack bar 2 with the construction specified by forming through the upper end of said head one or more holes 21 (Fig. 3) through which a punch may conveniently be inserted to swage over the upper edge of the tenon 15 into the countersink of the 25 socket 16. The base 6 is preferably provided with the usual teeth 22 on its under side to enable it to readily and strongly grip the surface on which it rests.

In Figs. 7 and 8 I have illustrated a 30 slight modification of the rigid tooth adjustment between the frame and the base. In this form of the invention, the base 6' is formed with parallel upstanding lugs 7', and the side walls of the main frame or 35 casing are provided with offset extensions or lugs 11' that overlap the lugs 7', and said lugs are connected, with capacity for pivotal adjustment, by means of pivot pins 9' passing through holes in the lugs 11' 40 and through slots 12' in the lugs 7'. In this form of the invention the lower edges of the laterally offset frame lugs or extensions 11' are provided with ratchet teeth 23 that co-operatively engage a series of ratchet 45 teeth 24 formed on the base 6' just outside the bases of the lugs 7'.

Figs. 9, 10 and 11 illustrate a still further modification of the same structural principle. In these figures 6^a designates the 50 base member formed with a pair of parallel upstanding lugs 7^a. Between said lugs is formed a concave gear rack 25. Each of the lugs 7^a is formed on its upper edge with a rounded, substantially semi-circular 55 seat portion 26 and with a flat horizontal stop shoulder 27. The lower end of the frame 1^a is, in this case, solid, and is formed with a central semi-circular lug 28 that fits between the upstanding lugs 7^a of the base 60 and is formed with a semi-circular rack 29 that engages and co-operates with the base 55 rack 25 in the manner clearly shown in Fig. 11. The side lugs 7^a are apertured, and the central lug 28 is slotted, as shown at 65 in Fig. 11, to accommodate a through pivot

pin 31. The lower ends of the opposite sides of the frame 7^a are formed with concave shoulders 32 that rest upon the convex seats 26 and relieve the pivot bolt 31 of the strain. The lower ends of the sides are 70 also formed with straight shoulders 33 that, when the frame is in vertical position, engage the stop shoulders 27 of the base.

From the foregoing it will be readily seen that in all of the forms shown and 75 described the teeth carried by the frame or casing engage with and rest securely upon the teeth on the base member, thus securely holding the jack casing and its contained parts rigidly with relation to the base; also that, in order to change the angular position of the frame, as from the vertical position shown in Fig. 1 to the inclined position shown in Fig. 2, it is necessary only 80 to grasp the frame, raise it to the extent 85 permitted by the slotted pivotal connection with the base, tilt or lean it to the desired angle, and allow it to return by gravity to a new position relatively to the stationary 90 rack on the base.

Fig. 12 illustrates a modified form of the swiveled head, wherein the head 4^a is made oblong and is provided with central and end notches 34 and 35, respectively, for engagement with alternate links 18 of such a chain as is shown in Fig. 2, and, between the notches 34 and 35, with sockets 36 adapted to seat the intermediate links 19 of the chain. Both of the swiveled heads illustrated in 100 Figs. 1 to 4 inclusive and in Fig. 12 engage the chain in a secure and anti-slip manner and without requiring any special fastening of the chain to the head.

Fig. 13 illustrates a very simple and convenient form of handle bar 14 which is 105 formed at one end with a diamond point 14^a adapted to enter the socket 5^a or 5^b of the socket member 5, in the manner shown in Fig. 2; and at its other end with a toe 14^b adapting the same to serve the purposes of a 110 pinch bar in wrecking service, while the opposite end 14^a serves the auxiliary purpose of a "diamond" point bar. While the lifting tool of the invention is preferably double or equipped with a handle member of the 115 form and functions last illustrated and described, in order to enhance the all-around utility of the tool as a whole, it will, of course, be understood that so far as the main structural features are concerned, they are not limited to that use in combination with this special form of handle.

From the foregoing description, taken in connection with the drawings, the utility and advantages of my invention will be 120 readily apparent. Where the tool can be applied directly to or beneath the article or object to be raised, it is applied in the vertical form shown in Fig. 1, with the head or 125 the foot of the jack directly engaged with 130

the object to be raised, and the handle bar preferably in the upper socket 5^a of the socket member 5. Where a thrust is to be imparted in an inclined direction, the tool 5 is adjusted to the position typically illustrated in Fig. 2, for which adjustment it is necessary only to lift the jack frame and its contained parts, tilt it angularly relatively to the base, and let it drop. If a low-lying object is to be raised that cannot be reached by the foot 3, the chain of the grapple can be applied to the swiveled head as shown in Fig. 2 with the grapple 20 at the proper height, and the object elevated in this 15 way. If the object is to one side of the jack, rather than directly in front of it, the swiveled head can be swung in either direction, thereby carrying the chain and grapple to either side of the jack.

20 The last described operations are equally capable of being performed with the apparatus when constructed in the manner shown in Figs. 1 to 6 or in the manner shown in Figs. 7 and 8, or in the manner shown in Figs. 9 to 11. It will thus be seen that the tool of the invention amounts, in effect, to a portable crane of what might be termed the lifting jack type. I am aware that it is old and known, broadly, to mount the frame of a lifting jack and its contained parts pivotally upon a base, with stops on the latter serving to limit the extent of swing of the frame to either side of the vertical. So far as I am aware, however, my present invention 30 is the first to provide a tool wherein the frame of the jack can be adjusted to and rigidly held in any of a number of relatively inclined positions by merely raising the frame of the tool, tilting it to the desired angle, and allowing it to drop into a position of rest relatively to the base. While I believe the means for effecting the described adjustability consisting essentially of the coöoperating teeth and the pin and slot 35 pivot are the best means for effecting this result, yet, in the broader aspects of the invention, I do not limit the same to these structural features which are common to all of the forms of the invention shown. In other respects, also, it will be evident to those skilled in the art that the described 45 details of construction may be considerably

modified without involving any departure from the principle of the invention or sacrificing any of the benefits and advantages 55 secured thereby.

I claim:

1. In a lifting appliance, the combination with the rack-bar of a lifting-jack, of a head on the upper end of said rack-bar 60 having formed thereon a chain-engaging seat comprising two like but oppositely disposed chain-guiding and holding means for engaging two vertically-standing links of a chain, and intermediate of said means a 65 space for the horizontally-lying link between said first two links.

2. In a lifting appliance, the combination with the rack-bar of a lifting jack, of an integral vertical tenon on the upper end 70 of said rack-bar, a head formed on its top side with seats for the links of a chain and having a socket in its bottom side by which said head is rotatably mounted on said tenon and an annular recess at the base of 75 said socket, and a flange on the upper end of said tenon coöoperating with said recess to retain said head on said tenon.

3. In a lifting appliance, the combination with the rack-bar of a lifting-jack of a 80 vertical, cylindrical tenon projecting integrally from the upper end of said rack-bar, a head rotatably mounted on said tenon, a vertical central socket in the lower side of said head, a circular recess undercut in said 85 socket, a flange swaged integrally from said tenon and engaging said recess, and means in said head for introducing a tool to swage out said flange after said head has been mounted on said tenon. 90

4. In a lifting appliance, the combination with the rack-bar of a lifting-jack, of a vertical cylindrical tenon projecting integrally from the upper end of said rack-bar, a head rotatably mounted on said tenon, 95 a flange on the upper end of said tenon coöoperating with a recess in said head to retain said tenon on said head, and a chain-guiding and chain-holding means for engaging two vertically-standing links of a 100 chain, and intermediate of said means a space for the horizontally lying link between said first two links.

WALTER B. TEMPLETON.
